UNITED STATES PATENT OFFICE.

JOHN B. ALBERS, OF LOS ANGELES, CALIFORNIA.

METAL-SAVING MACHINE.

No. 820,614.

Specification of Letters Patent.

Patented May 15, 1906.

Application filed November 24, 1905. Serial No. 238,950.

To all whom it may concern:

Be it known that I, JOHN B. ALBERS, a citizen of the United States, residing at Los Angeles, in the county of Los Angeles and State 5 of California, have invented new and useful Improvements in Metal-Saving Machines, of which the following is a specification.

My invention relates to that class of metal-saving machines in which the metal is dissolved by chemicals; and the object thereof 10 is to produce a machine in which the metal will be extracted from the pulp in a more expeditious manner than can be accomplished by the machines in common use for that purpose. I accomplish this object by the mechanism described herein and illustrated in the accompanying drawings, in which—

Figure 1 is a vertical section on the line 1 1 of Fig. 4. Figs. 2 and 3 are horizontal sections on the lines 2 and 3, respectively, of Fig. 1. Fig. 4 is a vertical section on the line 4 4 of Fig. 1. Figs. 5 to 8 are views illustrating details of different parts of the device herein-after described.

25 In the drawings, 10 is the building, which incloses the working parts of my machine. On the floor of the building is a mixing-trough 11, in which is rotatively mounted a shaft 12, provided with a pulley 13, to which power is applied to rotate the shaft. Secured to the end of shaft 12 nearest the driving-pulley are the mixing-bars 14, and at the other end of said shaft is a conveyer-screw 15, which forces the pulp out of the mixing-trough after it has been agitated by the mixing-bars. The pulp is forced by the conveyer-screw 15 into a receiving-chamber 16 and is carried out of said chamber by buckets 17, which are carried by sprocket-chains 18 30 and 19, forming an elevator. These chains pass over and are driven by sprocket-wheels 20 and 21, which are mounted upon driving-shaft 22, on which is mounted driving-pulley 23, to which power is applied to drive the shaft. These chains also pass over the idler or direction-changing sprocket-wheels 24 and 25, located above sprockets 20 and 21, and also over sprocket-wheels 26, which guide the 35 other side of the conveyer. The pulp is deposited by buckets 17 upon the top covering 27 of the aerating-tanks 28 and 29. In this top covering are hinged doors 30 and 31. When door 30 is opened, the pulp will pass into tank 28, and when door 31 is open the 40 pulp will pass into tank 29, door 30 being closed.

Extending transversely the aerating-tanks are a large number of triangular-shaped agitating-bars 32, which are placed therein with their apexes upwardly, and the alternate rows are staggered or stepped, so that as the pulp passes between them it will be compressed slightly and when it reaches the next row it will be subdivided at a new point, thus cutting and compressing alternately in different parts of the pulp as it passes downwardly through the tanks. At regular distances also, preferably extending transversely the aerating-tanks, are air-distributing conduits 33, which are also preferably triangular in shape, with their apexes projected toward the top of the tanks, and the alternate rows are preferably staggered for the same reason that the agitating-bars are staggered. In the bottom of the air-distributing conduits 75 are the air-ports 34, through which the air passes into the tanks. Below the agitating-bars are the filtering-frames, of which there are preferably one on each side and two in the center, as best shown in Fig. 4, although there 80 may be more or less of these frames, according to the capacity of the machine. These filtering-frames are composed of slats 35, which are covered with canvas or other cloth 36.

85 In Fig. 5 I have shown the form of the slats that are used next to the outside walls, and in Fig. 6 I have shown the form of the slats that are used in the center. The filtering-frames are preferably more widely separated 90 at the top than at the bottom, as best shown in Fig. 4, as thereby a somewhat greater filtering capacity is provided in a given space than if vertical, and they rest upon supporting base-frames 37. Below these base-frames 95 are the combined adjusting and moistening valves 38, which are hollow and are provided at one end with a hollow trunnion 39, through which water or chemical solution may be admitted into the interior, if desired. At the 100 other end, trunnion 40 is provided with an operating-handle 41, by means of which the valve may be turned partially or wholly across the opening between the base-frames 37. Below these valves is a screw conveyer 105 42, which forces all material passing the valves into passage-way or channel 43, through the bottom of which passes an elevator composed of buckets 44 and sprocket-chains 45, which are driven by sprocket-wheels 46, mounted on shaft 47, which last shaft is provided with driving-pulley 48, to 110

which power is applied. These buckets carry the material to the top of the building and deposit the same upon deflector 49. If the material is so far treated that it is only necessary that it should be passed through the final aerating-tank 50, the deflector is turned, as shown in full lines in Fig. 4, to carry the material into this tank. If the pulp requires a greater amount of treatment than can be obtained by passing it through the final aerating-tank to extract all of its values, the deflector is turned, as shown in dotted lines in Fig. 4, so as to carry the material and deposit it in the aerating-tanks 28 or 29, as desired. As shown in Fig. 4, the final aerating-tank is at a much higher elevation than the first aerating-tanks, so that when the material is forced out of the same by a screw conveyer 51 it is carried therefrom by suitable means to the dump. (Not shown.)

It will be understood that the ore, crushed to the required degree of fineness, is fed into the mixing-trough with the required amount of solution for the proper treatment of the ore, and that it is elevated to and deposited into the top of the aerating-tanks, and that air under the required degree of compression is furnished to compartment 52 through pipe 60 from a suitable source of supply, (not shown,) and that as the pulp passes down through the aerating-tanks a constant supply of compressed air is forced through the same at as many different levels as may be desired, and that the pulp is subjected to an alternate compression and expanding process and is alternately subdivided at different points as it passes downwardly through the aerating-tanks, and that when it passes between the filtering-frames a very considerable portion of the liquid passes through the canvas and into a channel 53 at the end of the filtering-frames of the aerating-tanks 28 and 29, from which it is elevated by pump 54 through pipe 55 into a settling-tank 56. From the final aerating-tank the liquid is elevated by pump 57 through pipe 58 into the settling-tank 56. The final aerating-tank is constructed in all particulars like aerating-tanks 28 and 29, except that it is not as long and terminates at a higher elevation, preferably, so as to provide convenient means for handling the refuse material. The air-conduits are connected to an air-compartment 59, which is supplied with air from pipe 60 through ports 61 therein.

It will be seen that in the operation of my machine it is desirable first to fill up the aerating-tanks 28 and 29 to the top and to regulate the flow of the material thereafter therethrough by valves 38, so that a large percentage of the liquid filters out through the canvas of the filtering-frame. As the material passes out of the tanks fresh material is fed in. Should the material have a tendency to clog in the lower parts of the filter-

ing-frames, by rotating valves 38 so as to bring ports 38' so that they open into the space between the base-frames 37, water or solution can be forced through the valves and out of the ports to moisten the material, so that it will readily flow through the conveyer-screw 42. Should the material get clogged in the screw, the valves can be rotated so as to bring the parts to bear thereon and the material can be washed out of the conveyer-screws by forcing water or solution through the valves.

Having described my invention, what I claim as new, and desire to secure by Letters Patent, is—

1. In a metal-saving machine an aerating-tank provided with a plurality of triangular-shaped agitating-bars arranged in stepped relation to those immediately above; air-tubes having ports therein extending across the aerating-tank; and filtering-screens at the bottom of said tank.

2. In a metal-saving machine an aerating-tank provided with a plurality of triangular-shaped agitating-bars arranged transversely the tank in stepped relation to those immediately above; air-tubes extending across the aerating-tank said tubes having ports therein; filtering-screens at the bottom of said tank; and means to elevate and discharge the material to be treated into the top of the tank.

3. In a metal-saving machine an aerating-tank provided with a plurality of triangular-shaped agitating-bars arranged in stepped relation to those immediately above; triangular-shaped air-tubes having ports therein extending across the aerating-tank; filtering-screens at the bottom thereof having passages therebetween; and regulating-valves on said passages.

4. In a metal-saving machine, an aerating-tank provided with a plurality of triangular-shaped agitating-bars arranged transversely the tank in stepped relation to those immediately above; triangular-shaped air-tubes extending across the aerating-tank; filtering-screens at the bottom of said tank having passages therebetween; regulating-valves on said passages; a conveyer-screw below said valves; and means to carry material from the end of said conveyer-screw to the top of the tank.

5. In a metal-saving machine; an aerating-tank provided with a plurality of triangular-shaped agitating-bars arranged transversely the tank in stepped relation to those immediately above; means to elevate and discharge the material to be treated into the top of the tank; triangular-shaped air-tubes having ports therein, said tubes extending across the aerating-tank; filtering-screens at the bottom of said tank having passages therebetween; regulating-valves on said passages; a conveyer-screw below said regulating-valve; and

means to carry material from the end of said conveyer-screw to the top of the tank.

6. In a metal-saving machine, an aerating-tank provided with a plurality of triangular-shaped agitating-bars arranged in rows, those in one row being arranged in stepped relation to those in the row immediately above; means to elevate and discharge the material to be treated into the top of said tank; means to 5 convey the material to said conveyer; triangular-shaped air-tubes extending across the aerating-tank, said tubes having ports therein; filtering-screens at the bottom of said tank having passages therebetween; regulating-valves on said passages; screw conveyers beneath said valves; and means to 10 carry the material from said screw conveyers to the top of the tank.

7. A metal-saving machine comprising a 20 plurality of aerating-tanks, each tank being provided with a plurality of triangular-shaped agitating-bars arranged in rows, those in one row being arranged in staggered relation to those in the row immediately above; 25 means to elevate and discharge the material to be treated into the top of said tank; a cover for said tanks upon which said material is received; doors in said cover, one for each tank; means to convey material to said 30 conveyer; triangular-shaped air-tubes extending across the aerating-tanks, said tubes having ports therein; filtering-screens at the bottom of each of said tanks, said screens

having passages therebetween, regulating-valves on said passages; screw conveyers beneath said valves; and means to carry the material from said conveyers to the top of the tanks; a settling-tank; and means to convey liquid filtered through said screen into 35 said settling-tank.

8. In a metal-saving machine; a plurality of aerating-tanks; a plurality of triangular-shaped agitating-bars arranged in rows in each tank, those in one row being arranged in staggered relation to those in the row immediately above; means to elevate and discharge the material to be treated into the top of said tanks; means to convey the material to said conveyer; triangular-shaped air-tubes 40 extending across the aerating-tanks; said tubes having ports therein; filtering-screens at the bottom of said tanks having passages therebetween; regulating-valves on said passages; screw conveyers beneath said valves; means to carry the material from said screw 45 conveyers to the top of the tanks; and means to carry the material from the conveyers to any of the tanks as desired.

In witness that I claim the foregoing I have hereunto subscribed my name this 17th 50 day of November, 1905.

JOHN B. ALBERS.
